CLAIM

The ornamental design for an electronic device for charging, data storage, or data transfer, as shown and described.

DESCRIPTION

FIG. 1 is a front, first side, and top isometric view of a first embodiment of an electronic device for charging, data storage, or data transfer embodying the new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a first cross-section view thereof along lines 8-8 in FIG. 6; and

FIG. 9 is a second cross-section view thereof along lines 9-9 in FIG. 6

FIG. 10 is a front, first side, and top isometric view of a second embodiment of an electronic device for charging, data storage, or data transfer embodying the new design;

FIG. 11 is a front view thereof;

FIG. 12 is a rear view thereof;

FIG. 13 is a first side view thereof;

FIG. 14 is a second side view thereof;

FIG. 15 is a top view thereof;

FIG. 16 is a bottom view thereof;

FIG. 17 is a first cross-section view thereof along lines 17-17 in FIG. 15; and,

FIG. 18 is a second cross-section view thereof along lines 18-18 in FIG. 15.

The broken lines in the drawings depict portions of the electronic device for charging, data storage, or data transfer that form no part of the claimed design.

The fine shade lines indicate the character and contour of the surfaces represented, not to be confused with surface ornamentation.

In the second embodiment, the stippled top portion of the electronic device for charging, data storage, or data transfer depicts a contrast in appearance.
